US0D1056373S

(12) **United States Design Patent** (10) **Patent No.:** **US D1,056,373 S**
(45) **Date of Patent:** **** Dec. 31, 2024**

(54) **VACUUM CLEANER**

(71) Applicant: **SHENZHEN TRANSSION HOLDINGS CO., LTD.**, Shenzhen (CN)

(72) Inventors: **Yiqi Jiang**, Shenzhen (CN); **Wenxian Jiang**, Shenzhen (CN)

(73) Assignee: **SHENZHEN TRANSSION HOLDINGS CO., LTD.**, Shenzhen (CN)

(**) Term: **15 Years**

(21) Appl. No.: **29/875,235**

(22) Filed: **May 1, 2023**

(30) **Foreign Application Priority Data**

Nov. 8, 2022 (CN) 202230744227.2

(57) **CLAIM**

The ornamental design for a vacuum cleaner, as shown and described.

DESCRIPTION

FIG. 1 is a front, left and top perspective view of a vacuum cleaner showing our new design;
FIG. 2 is a rear, right and bottom perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is a partial enlarged view taken from circle 9 in FIG. 1.

The dash-dash broken lines in the drawings depict the portions of the vacuum cleaner which form no part of the claimed design.

The dot-dash broken lines in the drawings depict the boundaries of the partial enlarged views that form no part of the claimed design.

1 Claim, 9 Drawing Sheets
